UNITED STATES PATENT OFFICE

2,096,383

AUTOMATIC FIRE EXTINGUISHING SYSTEM

Jay Lawrence Seat, Fairfield, Conn., assignor to
Mergenthaler Linotype Company, a corpora-
tion of New York

Application December 30, 1935, Serial No. 56,748

14 Claims. (Cl. 169—9)

This invention relates to new and useful improvements in fire extinguishing systems and has particular reference to an automatic chemical spray system adapted to be installed in buildings and the like to protect the same from serious damage by fire.

In accordance with the invention, there is provided a supply tank wherein the chemical fire extinguishing fluid is stored, an air compressor for maintaining a suitable pressure head in the tank and a pipe line leading from the storage tank to a plurality of sprinkler heads arranged at strategic points about the building to be protected.

This application is a continuation in part of my copending application, Serial No. 621,223, filed July 7th, 1932, which has matured into Patent 2,025,782, and the sprinkler heads disclosed and claimed in that application are of the type preferably used in the system herein disclosed. As shown in the application referred to, the sprinkler heads are normally maintained closed by fusible links adapted, upon a temperature rise such as that experienced in the vicinity of a fire, to melt, thus allowing the sprinkler heads to open to effect the discharge of the fire extinguishing fluid. Also, in accordance with the invention, the opening of the sprinkler heads or any of them will effect the closing of an electrical circuit through a motor which operates the compressor, so that at any time during the operation of the system, a sufficient pressure head will be maintained in the storage tank properly to effect the discharge of fluid. In addition, a supplementary electric circuit is provided for operating the motor and which is controlled by a pressure operated switch responsive to the pressure in the storage tank. The pressure switch is so constructed as to maintain the pressure in the system between predetermined lower and upper limits, i. e., should the pressure in the system drop as a result of partial usage of the liquid or leakage in the system, the pressure operated switch will cut in the motor when the pressure has dropped to a predetermined lower limit and will automatically operate to cut out the motor when the pressure has again been built up to a predetermined upper limit.

The system is essentially what is known as a dry pipe system, i. e., there is no liquid in the pipes or headers with which the sprinkler heads are associated when the system is in its normal inoperative condition, a pressure head of air being maintained in such pipes substantially equal to that in the storage tank. However, upon the opening of a sprinkler head, the accompanying

drop in pressure in the pipe system will allow the fluid to be forced from the tank to the sprinkler heads for discharge therefrom.

It is apparent that, should leaks develop in a system of this character, the advantages thereof will be lost, since it is obvious that the reduction in pressure in the pipe system will allow the liquid to pass from the tank to the sprinkler heads even without any of the latter being opened. In order to prevent this and maintain the system dry at all times, there is provided, in accordance with the invention, a bypass connected between the storage tank and a point in the riser leading from the storage tank to the distributing pipes, at a level above that of the liquid in the tank. In the bypass there is located a valve normally biased to an open position and which permits the pressure in the storage tank and pipe system proper to be maintained the same. However, upon the opening of a sprinkler head, resulting as it does in a substantial drop of pressure in the system, a large pressure differential will be created between the storage tank and the pipe system sufficient to effect the closing of the valve. When the valve has closed, the only communication between the storage tank and the sprinkler heads will be through the liquid pipe lines, and consequently the liquid will be forced from the storage tank to the sprinkler heads for discharge therefrom.

Referring to the drawing:

Fig. 1 is a front elevation, partly diagrammatic, and illustrating a system involving the present invention;

Fig. 2 is a detail view, partly in section, showing the bypass between the storage tank and the header leading to the pipe system; and

Fig. 3 is a schematic circuit diagram of the pressure operated switch for cutting the compressor in and out between the lower and upper pressure limits.

As shown in Fig. 1, the fire extinguishing system includes a storage tank 5 mounted on any suitable support 6 and partially filled with a chemical fire extinguishing fluid 7, as for example, carbon tetrachloride. Above the liquid in the tank, there is reserved a space 8 wherein a suitable head of air may be built up. Connected with the space 8 above the liquid is an air compressor 9 which for convenience may be mounted on a stand 10 located on the tank and connected through the medium of a pipe 11 with the air space 8 just alluded to.

The compressor 9 is driven at the proper time by an electric motor 12 acting through an endless

belt or other power transmitting means 13. The liquid 7 is preferably maintained under a pressure head of not less than thirty pounds per square inch, and to this end means are provided 5 whereby, when the pressure within the tank drops below a predetermined minimum, the motor 12 is automatically started to operate the compressor and build up the pressure within the tank to the desired head. A power supply line is indicated at 10 14 and has connected with it a line 15 leading to a suitable pressure switch 16 in communication with the interior of the tank 5 through a pipe 17. By way of illustration, the pressure switch 16 (see Fig. 3) may include a Bourdon tube 16^a communicating with the tank 5 through the pipe 17 and having an electrical connection with the power line 15. Normally the switch 16 is open, but when the pressure in the tank falls below the predetermined minimum, the Bourdon tube 16^a 15 will coil up until it touches the contact 16^b which is connected by the lead 18 with one of the wires 19 leading to the motor 12. A return lead 18^a between the other wire 19 and the line 15 completes the circuit through the motor to drive the compressor. When the pressure in the tank 5 again reaches the desired head, the Bourdon tube 16^a uncoils, breaking the circuit, and stopping the motor. The power line 14 is also connected with the wires 19 through a normally opened 20 switch 20^a. One element of the switch is the armature of a relay 20 which is connected to the power leads 14 through the lead 20^b, the lead 38, grounded on the system, the leads 35, 36, and switches on the sprinkler heads later to be described. The switch 20^a, connecting the leads 14 with the motor 12, is normally opened, but when any of the sprinkler heads are rendered operative, the relay 20 is energized to close the switch 20^a to complete the circuit through the motor. 25 30 A pipe 21 is in communication with the lower portion of the interior of the tank 5 and connected with this pipe 21 is an upright pipe or riser 22 from which extend suitable laterals or branches 23, the number of which will vary according to the structure to be equipped with the apparatus. At suitable intervals along the pipes 23, there are provided sprinkler heads 24, preferably of the character disclosed in my copending application previously referred to, and which, it is thought, need not be described in detail here. Suffice it to say, however, a sprinkler head of the kind referred to, includes a body portion having a recessed chamber communicating with a pipe 23 and closed at one end by a plunger valve arranged to control the opening and closing of ports communicating with the chamber and through which the liquid is discharged. The valve is held in its port closing position against the action of a compression spring by a fusible link, which, in the event a fire occurs, will melt and allow the valve to be moved to port opening position under the influence of the air pressure in the system and the influence of the spring with which the sprinkler head is equipped. 35 40 45 50 55 60 65 70 75 Upon the opening of any of the sprinkler heads, a circuit will be completed through the relay 20, thereby effecting the closing of the switch 20^a, which in turn completes the circuit between the supply line 14 and the line 19 through the motor 12, whereby the motor will be energized to drive the compressor, all as previously described. From this it will be seen that, should the temperature increase in the vicinity of but one sprinkler head, that sprinkler head will open and the motor will be started to drive the compressor to maintain

the pressure on the fluid in the tank. The pressure on the fluid in the tank will cause its passage to the open sprinkler head and effect its discharge therefrom. Should more than one sprinkler head open at the same time or should the sprinkler heads open successively, the operation will be the same, fluid being sprayed from each open sprinkler head. 5

An audible or other signal 39 may be connected in parallel arrangement with the leads 19 to the motor, so that when the switch 20^a is closed upon the operation of the sprinkler head, a signal will be given. The signal, of course, may be located at any desired point. In order to facilitate testing the system, a switch 41 may be provided for 15 manually closing the circuit through the leads 35 and 38. A manually operable relief valve 42 is provided in the pipe line 11 which may be used to release the air pressure when starting the motor for test purposes. Also, a pressure gauge 43 20 is provided in the pipe line 11 in order that the pressure within the tank 5 may be determined at any time. The pipe line 22 is provided with a cut off valve 44 in order that communication between the tank 5 and the upright 22 may be cut 25 off when it is desired to drain the piping system as through the valve 45. The chemical fire extinguishing fluid may be supplied to the tank through an opening normally closed by a plug 46. 30

The system herein described is a dry pipe system, wherein air is trapped in the pipes leading to the sprinkler head, and were it not for the means presently to be described, the liquid 7, due to the pressure in the tank, would rise in the pipe 22 and escape should a leak in the system 35 occur. Such means include the pipes 46, 49 and a valve 48, together constituting a connection from the top of the tank 5 to the riser 22 at a point above the normal level of the liquid in the tank. The valve 48 is positioned at an angle of 40 approximately 45°, and has a flap 52 arranged to hang vertically therein. The valve is normally open, permitting communication between the tank and the riser 22, and its bias is such that a difference in pressure of about ten pounds between the tank and the pipe system is required to effect its closing. If small leaks occur in the pipe, the valve will remain open so that the pressures in the tank and pipe system become equalized and prevent the rise of liquid in the pipe 22 45 above the normal level of the liquid in the tank. Upon the operation of a sprinkler head, however, the pressure in the pipe system immediately drops (in excess of ten pounds below the tank pressure), closing the valve 52 and shutting off communication between the upper part of the tank and the riser 22, with the result that the liquid is forced up through the riser and discharged from the open sprinkler head. Should more than one 50 sprinkler head open at the same time, or should the sprinkler heads open successively, the operation will be the same. 55

From the foregoing description, it will be apparent that the chemical under pressure is immediately available upon the opening of a sprinkler head. This, of course, is due to the arrangement whereby the motor 12 is started and stopped automatically on the pressure within the tank 5 dropping below a predetermined minimum and reaching a predetermined maximum. Further, it will 60 be understood that immediately upon the opening of a sprinkler head, the motor 12 is started independently of the switch 16, so that the compressor will be actuated to build up or maintain the pressure within the tank, irrespective of whether 70 75

the same is at or below a predetermined minimum. Furthermore, as the circuit through the sprinkler heads is closed under the influence not only of the pressure in the system but also through 5 the action of the compression springs with which such sprinkler heads are equipped, it is evident that good electrical contact will be made.

In the accompanying drawing, the invention has been shown merely by way of example and in preferred form, and obviously, many variations and modifications may be made therein which will still be comprised within its spirit. It is to be understood, therefore, that the invention is not limited to any specific form or embodiment, except insofar as such limitations are specified in 15 the appended claims.

Having thus described my invention, what I claim is:

1. A fire extinguishing system of the sprinkler 20 type comprising a sprinkler head normally inoperative but adapted when operated to permit the discharge of liquid therefrom, a source of fire extinguishing liquid, means for connecting the source of liquid with the sprinkler head, an electrically operated motor driven air pump for producing 25 a pressure head on the liquid at the source so as to supply said liquid to the sprinkler head under pressure, an electric circuit connected to said motor and means acting independently of 30 the pressure in the system and functioning upon the operation of said sprinkler head to close the circuit through the motor.

2. A fire extinguishing system of the sprinkler 35 type comprising a sprinkler head normally inoperative but adapted when operated to permit the discharge of liquid therefrom, a supply tank for fire extinguishing liquid, means connecting the supply tank at a point below the level of the liquid therein with the sprinkler head, an electrically 40 operated motor driven air pump for producing a pressure head on the liquid in the tank so as to supply said liquid to the sprinkler head under pressure, an electric circuit connected to said motor and means acting independently of 45 the pressure in the system and functioning upon the operation of said sprinkler head to close the circuit through the motor.

3. A fire extinguishing system of the automatically 50 operated sprinkler type comprising a sprinkler head having fusible means normally maintaining it inoperative to discharge liquid, a source of fire extinguishing liquid, means connecting the source with the sprinkler head, an air pump for producing a pressure head on the liquid at the 55 source so as to supply said liquid to the sprinkler head under pressure, means for driving said pump, a source of power for said driving means and means functioning automatically upon the operation of the sprinkler head and independently of 60 the pressure in the system operatively to associate the source of power with the driving means to drive the pump.

4. A fire extinguishing system of the automatically 65 operated sprinkler type comprising a sprinkler head having fusible means normally maintaining it inoperative to discharge liquid, a supply tank for fire extinguishing liquid, means connecting the supply tank at a point below the level of the liquid therein with the sprinkler head, an air pump for producing a pressure head in the tank to supply liquid to the sprinkler head under pressure, means for driving said pump, a source of power for said driving means, and means functioning automatically upon the operation of 70 the sprinkler head and independently of the pres-

sure in the system operatively to associate the source of power with the driving means to drive the pump.

5. A fire extinguishing system of the sprinkler type comprising a sprinkler head normally inoperative but adapted when operated to permit the discharge of liquid therefrom, a supply tank for fire extinguishing liquid, a pipe connecting the tank at a point below the level of the liquid therein with the sprinkler head, an air pump 10 associated with the tank for maintaining a pressure head in the system, an electric motor for driving the pump, means operated by the air pressure in the system and controlling the electric motor to maintain said pressure above a predetermined limit, and other means functioning when the sprinkler head is rendered operative 15 also to control the motor which drives the pump.

6. A fire extinguishing system of the sprinkler type comprising a sprinkler head normally inoperative but adapted when operated to permit the discharge of liquid therefrom, a supply tank for fire extinguishing liquid, a pipe connecting the tank at a point below the level of the liquid therein with the sprinkler head, a pump associated 20 with the tank for maintaining pressure on the liquid in the system, an electric motor for driving the pump, means operated by the pressure in the system and controlling the electric motor to maintain said pressure above a predetermined 25 limit, and other means acting independently of the pressure in the system and functioning when the sprinkler head is rendered operative 30 also to control the motor which drives the pump.

7. A fire extinguishing system of the sprinkler 35 type comprising a sprinkler head having a valve and a fusible element associated therewith to normally maintain the valve inoperative to discharge liquid, a supply tank for fire extinguishing liquid, a pipe connecting the tank at a point 40 below the level of the liquid therein with the sprinkler head, an electrically operated motor driven pressure pump associated with the tank, means operated by the pressure in the system and controlling the operation of the pump for maintaining the pressure on the liquid in the tank above a predetermined limit, a circuit including 45 the motor, a pair of electric contacts in the circuit and arranged on the sprinkler head, and a spring associated with the sprinkler head, said 50 spring being adapted upon fusing of the fusible element positively to open the valve and close the contacts whereby the pump is caused to function independently of the pressure control.

8. A fire extinguishing system of the sprinkler 55 type, comprising a sprinkler head normally inoperative but adapted when operated to permit the discharge of liquid therefrom, a source of fire extinguishing liquid, a pipe connecting the source with the sprinkler head, an electrically operated 60 motor driven air pump for producing a pressure head on the liquid at the source so as to supply said liquid to the sprinkler head under pressure, a circuit for the motor, and an electric switch actuated by the sprinkler head when the latter 65 is rendered operative to close the circuit through the motor.

9. A fire extinguishing system of the sprinkler type, comprising a sprinkler head normally held inoperative by a fusible element, a source of fire 70 extinguishing liquid, a pipe connecting the source with the sprinkler head, an electrically operated motor driven air pump for producing a pressure head on the liquid at the source so as to supply said liquid to the sprinkler head under pressure, 75

an electric circuit for the motor, a switch actuated by the sprinkler head when the latter is rendered operative to close the circuit through the motor, and a spring for urging the head to operative position upon the fusing of the fusible element.

10. A fire extinguishing system of the sprinkler type, comprising a sprinkler head normally inoperative but adapted when operated to permit the discharge of liquid therefrom, a supply tank for fire extinguishing liquid, a pipe connecting the tank at a point below the level of the liquid therein with the sprinkler head, a compressor communicating with the tank, an electric motor 15 for driving the compressor, two control circuits for the motor, one circuit having a control switch operated by the pressure in the tank to maintain the pressure on the liquid therein above a pre-determined limit, and the other circuit having a 20 switch operated by the opening of the sprinkler head to start the compressor independently of the pressure in the tank.

11. In combination, a tank for the storage of liquid, a riser pipe communicating with the tank 25 substantially at the base thereof and extending above the level of liquid in the tank, a normally closed outlet for the pipe above the tank, a conduit between the tank and the riser pipe above the normal liquid level, means for creating a pressure 30 head of air in the tank and means associated with the conduit adapted to remain open during small pressure drops in the pipe to equalize the air pressure in the system, but adapted to close during large pressure drops in the pipe as when the pipe 35 outlet is opened to permit the discharge of liquid therefrom.

12. A fire extinguishing system including, in combination, a tank for the storage of liquid, means for maintaining a substantial pressure head 40 of air in the tank, a riser pipe communicating with the tank substantially at the base thereof and with a dry pipe system including sprinkler means arranged above the level of the liquid in the tank, said sprinkler means being normally closed 45 but capable of being opened under fire conditions, a normally open connection between the top of the tank and the riser pipe at a point above the

level of the liquid in the tank for maintaining the air pressure in the pipe system substantially equal to that in the tank, and means acting independently of the liquid flow for closing said connection upon the opening of the sprinkler means, whereby 5 the liquid may be forced from the tank through the riser pipe to the open sprinkler means.

13. A fire extinguishing system including, in combination, a tank for the storage of liquid, means for maintaining a substantial pressure 10 head of air in the tank, a riser pipe communicating with the tank substantially at the base thereof and with a dry pipe system including sprinkler means arranged above the level of the liquid in 15 the tank, said sprinkler means being normally closed but capable of being opened under fire conditions, a normally open connection between the top of the tank and the riser pipe at a point above the level of the liquid in the tank for maintaining the air pressure in the pipe system substantially 20 equal to that in the tank, and means acting automatically and directly as a result of the air pressure difference created upon the opening of the sprinkler means to close said connection whereby the liquid may be forced from the 25 tank through the riser pipe to the open sprinkler means.

14. A fire extinguishing system including, in combination, a tank for the storage of liquid, means for maintaining a substantial pressure 30 head of air in the tank, a riser pipe communicating with the tank substantially at the base thereof and with a dry pipe system including sprinkler means arranged above the level of the liquid in 35 the tank, said sprinkler means being normally closed but capable of being opened under fire conditions, a connection between the top of the tank and the riser pipe at a point above the level of the liquid in the tank, and a valve in said connection 40 normally biased to open condition to allow equalization of the air pressure in the tank and in the pipe system, said valve being adapted to close upon the opening of the sprinkler means whereby the liquid may be forced from the tank through the 45 riser pipe to the open sprinkler means.

JAY LAWRENCE SEAT.
